COMBINATION MUZZLE BRAKE AND GRENADE LAUNCHER FOR PORTABLE FIREARMS

Pier Carlo Beretta, Via Siepi 6, Gardone V.T.,

Brescia, Italy

Filed June 30, 1960, Ser. No. 40,495

Claims priority, application Italy Apr. 2, 1960

4 Claims. (Cl. 42—1)

Numerous prototypes of portable firearms (guns, pistols, etc.) actuated with "gas intake," have complementary devices adapted to transform occasionally the weapon into a bomb-thrower (or grenade-thrower) by utilizing a throwing charge that is made to explode in the barrel of the weapon. The gases generated by the explosion impart to the bomb fitted at the front end of the barrel the necessary impulse for detaching it from the weapon and covering a determined trajectory.

In order that the thrust of the gas should attain maximum effectiveness for the above object however it is necessary to avoid any dispersion thereof. Therefore, it is necessary that the "gas intake" that normally produces automatic operation of the weapon be occluded. The occlusion is obtained by means of interconnected valves applied to the "gas intake" device, which are actuated by hand. Their actuation however appears to be hindered sometimes by the presence of dirt, incrustations etc.; and it is to obviate that inconvenience that the device according to the present application was developed. The invention has the purpose of realizing in a simple and safe manner the occlusion (or in the contrary sense the opening) of the "gas intake" without having recourse to interconnected valves of greater complication and, moreover, by utilizing the manual operation needed to move to or from operative position the sight upright forming part of the sighting device of the bomb-throwing device so as to render such operations inter-dependent. Moreover, the device is organized in such a way as to operate as an effective muzzle-brake or stabilizer of a weapon subject to with recoil as well as with pitching.

Also the operation of the muzzle brake depends on the movement and on the position of said sight upright, since an external tube which forms a part of the muzzle brake displaces itself longitudinally upon movement of said upright to which it is mechanically connected.

Merely by way of example there is described herein-after the application of the invention to the American Garand Mod. 30 M1 rifle. However, it is pointed out that convenient modifications to the specific constructive characteristics of each individual type of weapon make application possible also to other similar weapons.

It should be noted before that with the cited Garand model rifle, the "gas intake" consists of a hole provided in the barrel in the proximity of the muzzle; that said hole is in communication with the interior of the "gas intake cylinder" fixed below the barrel by means of suitable ferrules; and that the temporary interception of the passage of gas between barrel and cylinder is effected, when one wishes to actuate the original bomb-throwing device of the weapon, by means of a valve applied to the front end of said cylinder and held open by the bomb-throwing device, while this prevents automatic operation of the weapon, it causes the dispersion into the atmosphere of a considerable amount of gases generated by the charge which, therefore, are not totally exploited for the purposes of the bomb-throwing because the effect of the valve then is to establish a momentary communication between the interior of the chamber and the atmosphere preventing thereby the operation of the piston which slides in the gas intake cylinder.

With the invention hereinafter described the hole pro-

vided radially in the barrel remains unaltered and so remains unaltered in its shape and in its function. The "gas intake cylinder" below the barrel, however, is not fixed rigidly to the barrel but is mounted slidably thereon, so that a displacement of the cylinder in the longitudinal direction suffices to interrupt the communication between the interior of the barrel and the interior of the cylinder or, if operation is in reverse sense, to restore it.

Moreover, that longitudinal displacement in the two directions is obtainable by operating a lever with which the cylinder is connected and which is susceptible of rotation in the vertical plane. Said lever constitutes moreover the upright of the sight for the bomb-thrower.

As a consequence the operation necessary to prepare the sight for bomb-throwing causes immediately the occlusion of the "gas intake" device, which occlusion is necessary, as has been seen, to ensure maximum throw range for the bomb. Vice versa, when one wishes to utilize the weapon for its normal use, the return of the upright of the sight to its inactive position causes the longitudinal displacement of the cylinder in reverse sense, thus restoring the normal operation of the "gas intake," and, consequently, the normal condition of the devices for closing, cocking and feeding said weapon for the purpose of its operation as an automatic rifle.

Reference is made here to the embodiment illustrated by mere way of example in the accompanying drawings wherein:

FIG. 1 represents the device in axial (longitudinal) section when the weapon is prepared for operation as a rifle;

FIG. 2 represents a partial section along the line 2—2 of FIG. 1;

FIG. 3 represents the device of FIG. 1 but prepared for operation of the weapon as a bomb-thrower;

FIG. 4 represents a partial section taken along the line 4—4 of FIG. 3;

FIG. 5 represents a cross-section of the device taken along the line 5—5 of FIG. 3;

FIGS. 6 and 7 show the slideable ferrule 5 in side and front views respectively; and

FIGS. 8 and 9 show the fixed ferrule 7 in side and front views, respectively.

With reference to the accompanying drawings: in FIG. 1 is illustrated the device applied, by way of example as already said, to the Garand Mod. 30 M1 semi-automatic rifle. The sight upright 14 of the bomb-thrower is down and, consequently, the "gas intake" hole of the barrel is in correspondence with the "bore" provided in the wall of the cylinder and, therefore, there is direct communication between the barrel and cylinder. In said position the weapon is ready for operation as an automatic rifle.

With reference numeral 1 is indicated the barrel of the weapon which has the radial hole or "gas intake" 2 in communication through port 3' with the interior of the cylinder 3 which encloses the devices used in the automatic operation of the rifle. The cylinder 3 is closed by a plug 4 and is mounted on the barrel 1 by means of a ferrule 5 susceptible of longitudinal sliding. On the muzzle end of the barrel there is screwed the trumpet tube 6 which constitutes an extension of said barrel and is destined to support the bomb which is to be thrown. (It should be noted that the application of said extension 6 does not prejudice, in any way, the operation of the weapon as an automatic rifle). The trumpet tube 6 in fact has an axial bore with a gauge not less than that of the barrel and has, in its bore one or more chambers where its bore diameter is sensibly widened; and has conveniently arranged slits in the wall of the trumpet tube 6 which put these chambers in communication with the atmosphere.

In FIG. 3 is illustrated the device prepared for operation as a bomb-thrower. Consequently, the operation of the weapon as an automatic rifle is temporarily prevented.

The sight upright 14 is brought by hand to vertical position and by effect of said movement and of the devices hereinafter described, the cylinder 3 is compelled to slide backwards just as much as needed in order that the hole 2 for "gas intake" is no longer aligned with port 3' and the interior of said cylinder. In that way the entire volume of the gas generated by the explosion of the cartridge is available at the mouth of the barrel for the action of throwing the bomb which is to be fitted into the extension 6.

The assembly and operation of the device are as follows. On the perforated cylindrical extension 6 (the external diameter of which and the length of which will be dimensioned in relationship with the weapon and with the type of bomb one intends to adopt) is fitted the ferrule 7 provided with a forked extension 7' in whose furcations there are provided the holes 8 that hold the pin 9. The ferrule 7 is then secured to the body 6.

Behind ferrule 7 there is mounted to slide, again on the extension 6, a second ferrule 5 which is shaped at its top as a fork with furcations 12 and which by means of a ring 13 below and rigid therewith, can embrace the head 4 of the plug of the gas intake cylinder 3. On the pin 9 which finds housing in the holes 8 of the fixed ferrule 7, there are mounted, in symmetrical position with respect to the vertical axial plane of the weapon, the cam 15 and the sight upright 14 connected to the pin 9 by means of suitable adjustments, so as to be rigid therewith. The pin 9 terminates at one side in a fixed button and at its other side in a counter-nut secured to the pin 9 by means of a removable member (split or cotter pin or the like).

The assembly so mounted is then screwed onto the muzzle of the gun, as an extension thereof.

If the upright of the sight is down, namely held in horizontal position (FIG. 1), the gas intake hole 2 in the barrel is in register with the bore of the cylinder 3 through the corresponding port 3'. At the time of the firing of the cartridge, part of the gases passes therefore from the barrel to the interior of the cylinder and actuates the device provided for the automatic operation of the rifle. If the sight upright 14 is turned manually 90° to the vertical position of FIG. 3, the weapon is automatically prepared for operation as a bomb-thrower.

In fact as a consequence of the rotation imparted to the upright 14 which is rigid with the pin 9 mounted on the ferrule 7 fixed to the body 6, the cam 15 that rotates rigid with the upright 14, acting upon the symmetrical fork 12 of the slidable ferrule 5, compels the latter to move rearwardly while sliding on the exterior of the body 6. Since the ferrule 5 embraces, by means of the ring 13, the head 4 of the closing plug for the cylinder 3, also the latter is compelled to slide backwards and to the same extent. Consequently the external surface of the cylinder 3 closes the hole 2 or "gas intake" provided in the barrel, thereby intercepting the gases normally directed to the interior of the cylinder 3 and preventing the operation of the devices that have relationship with the automatic operation of the rifle. The entire volume of the gas generated by the explosion is so available for the throwing of the bomb.

The rotation in reverse sense of the aforesaid sight upright 14 causes an effect contrary to the one just described and the weapon is restored to initial position as illustrated in FIG. 1 and, therefore, it can resume its operation as an automatic rifle.

Moreover, the extension of the barrel 6 or the trumpet tube, which is bored and perforated, as stated, in order to permit passage of the bullet and of the gases has one or more chambers 17 in the walls of which there are provided through slits 18 which permit the partial dis-

charge of the gases to the atmosphere. These slits are, however, occludable by means of a pipe 19 mounted concentrically with the extension 6, slidable thereon and having perforations 19' therein alignable with the slits 18 in the chambers 17.

Said pipe 19 has two fins 20 which extend as far as the slidable ferrule 5 already mentioned, to which they are fastened by means of pins 21 and 21' which pass through holes 5' in ferrule 5.

The consequence is that when the rotation of the sight upright 14 effected by hand, causes the displacement of the slidable ferrule 5, said movement causes also the rectilinear and contemporaneous displacement of the gas intake cylinder 3 and the tube 19.

With reference to FIG. 1, which represents the weapon prepared for operation as a rifle, it will be noted that the sight upright is down, that the gas intake opening between the barrel 1 and the cylinder 3 is free and that the slits 18 are uncovered or aligned with perforations 19'. Consequently the shooting of a cartridge causes the normal operation of the rearming mechanism of the weapon and the propulsion of the bullet. Moreover the gases that expand in chamber 17 partly escaped to the outside through the slits 18 which are open, thereby exerting an effective action of muzzle brake for the rifle.

With reference to FIG. 3, which represents the weapon as prepared for operation as a bomb-thrower, it will be noted that the upright of the sight has been erected to vertical position; that by effect of that movement and of the connections existing the gas intake aperture between the barrel 1 and the cylinder 3 has become closed; and that the slits 18 have been covered by the tube 19.

Consequently the gases generated by the shooting of the cartridge cannot enter the cylinder 3 nor can they actuate the rearming mechanism of the weapon. Moreover, since the slits 18 are closed, the entire volume of said gases remains available at the mouth of the trumpet tube 6 to impart to the bomb applied thereto the maximum possible throw range.

I claim:

1. The combination with a portable firearm having a barrel with a port therein and through which the gases of firing may escape to effect automatic operation of said firearm, of a combined grenade-launching and muzzle-braking device for said firearm comprising a tubular member secured to said barrel coaxially thereof to project forwardly beyond the muzzle end of said barrel, said tubular member having a plurality of ports extending through its wall, and a member mounted on said tubular member to slide axially thereof and having a plurality of ports therethrough, which are adapted to be moved by sliding movement of said last-named member in opposite directions into and out of registry with the ports of said tubular member to render said muzzle brake operative and inoperative, respectively, and closure means secured to the last-named member and operative upon movement of said last-named member in opposite directions, respectively, to open and close the first-named port in said barrel, respectively.

2. The combination as claimed in claim 1 wherein said closure means includes a cylinder mounted on said barrel with its axis parallel to the axis of said barrel for movement in the direction of the axis of said barrel and having an opening therein which upon movement of said last-named member in opposite directions is moved into and out of alignment with said first-named port, said cylinder operating, when said opening is out of alignment with said first-named port, to close off the latter to prevent the escape of gases therethrough.

3. The combination as claimed in claim 1 wherein a cam is rotatably mounted on said tubular member and is operatively connected both to said last-named member and to said closure means, and manually-operable means is provided for rocking said cam in opposite directions

to effect simultaneous movement of said last-named member and said closure means in one direction or the other depending upon the direction of movement of said cam.

4. The combination as claimed in claim 3 wherein said manually operable means comprises a grenade launching sighting lever secured at one end to said cam and pivotal between a vertical position in which it extends normal to said tubular member, and a horizontal position parallel to said tubular member, said lever being operative upon movement to its vertical position to rotate said cam in a

10

direction to cause said ports in said last-named member to be positioned out of registry with the ports in said tubular member and to close said first-named port.
